United States Patent Office

Des. 197,296
Patented Jan. 7, 1964

197,296

PLATE OR THE LIKE

Herbert I. Dann, Jr., 10 Taylor St., Painted Post, N.Y.

Filed Sept. 4, 1963, Ser. No. 76,478

Term of patent 14 years

(Cl. D44—15)

The FIGURE is a top plan view of a plate of conventional configuration showing my new design.

I claim:

The ornamental design for a plate or the like, as shown and described.
